UNITED STATES PATENT OFFICE.

MICHAEL C. HARNEY, OF ST. LOUIS, MISSOURI, ASSIGNOR OF ONE-HALF TO
WILLIAM N. BRENNAN, ANN BRENNAN, AND MARY A. GRACE, ALL OF
SAME PLACE.

SEAL-LOCK.

SPECIFICATION forming part of Letters Patent No. 399,526, dated March 12, 1889.

Application filed September 1, 1888. Serial No. 284,348. (No model.)

To all whom it may concern:

Be it known that I, MICHAEL C. HARNEY, of the city of St. Louis, in the State of Missouri, have invented a certain new and useful Improvement in Seal-Locks, of which the following is a full, clear, and exact description, reference being had to the accompanying drawings, forming part of this specification, and in which—

- 10 Figure I is a side elevation of my improved seal-lock, showing it applied to a door of a railway-car. Fig. II is a side elevation of the seal. Fig. III is a similar view of the spring-catch. Fig. IV is an enlarged side elevation 15 of the bolt and spring and section of the seal. Fig. V represents a modification of the seal. Fig. VI represents another modification of same. Fig. VII is a modification of the 20 spring.
- 20 My invention relates to an improved seal, intended more particularly for use in securing the doors of railway-cars; and my invention consists in features of novelty herein-after fully described, and pointed out in the 25 claims.

Referring to the drawings, 1 represents the door-frame of a car, and 2 the door.

3 represents a hasp secured to the door, and which fits over a staple, 4, secured to the 30 frame.

5 represents a bolt that may be secured to the frame or body of the car by means of a chain, 6. The upper end of this bolt is preferably provided with a shoulder, 7, that prevents the bolt from moving downwardly out 35 of the staple, and the lower end of the bolt is preferably formed in hook shape, with an upturned end, 8. On this end of the bolt is a head, 9, formed with a shoulder, 10, which 40 would be made by an annular groove, 11, in the bolt beneath the head.

12 represents a spring, consisting, preferably, of a thin plate of metal having inturned ends 13. This spring fits over the head 9 of 45 the bolt, as shown in Fig. IV.

14 represents a seal that fits over the head 9 and over the spring 12, as shown in Fig. IV, and it has a shoulder, 15, at the upper end of a neck, 16. The lower extremities, 17, 50 of the spring fit against the shoulders 15 of the seal; (when the seal is applied as shown

in Fig. IV,) and the upper extremities of the points 13 fit against the shoulder 10 of the head 9.

In applying the seal the bolt is first inserted through the staple 4 after the hasp has been put on. Then the spring is placed over the head 9, and then the seal is placed over the spring and held to the bolt, as shown in Fig. IV. It will be seen that after the seal has been applied it will be impossible to get it off without destroying it, as the spring holds it firmly in place. The seal is of sufficient size to be incapable of passing through the staple 4, so that the bolt cannot be taken out of the staple without removing the seal. The seal is made of glass, clay, pottery, porcelain, or other fragile material, so that it may be easily broken by authorized persons.

In Fig. V, I have shown a different-shaped seal, where the edges are made circular and the sides flat, and in Fig. VI is still another modification, wherein four wings, 20, are used, and in Fig. VII, I have shown a modification of the spring, where four arms (instead of two, as shown in Figs. III and IV) are employed.

I have described the locking-spring as placed over the head of the bolt previous to its insertion within the seal; but when desired the spring may be previously placed within the seal and the point of the pin be made to engage with it as it is inserted in said seal.

I claim as my invention—

1. In a seal-lock, the combination of a bolt having a head forming a shoulder, a spring having ends fitting beneath the head of the bolt, and a seal having a shoulder engaging against the extremities of the spring, substantially as and for the purpose set forth.

2. In a seal-lock, the combination of the bolt formed with a hook or upturned end, a head on the end of the bolt, a spring having ends engaging beneath the head of the bolt, and a seal fitting over the head of the bolt and having a shoulder engaging the extremities of the spring, substantially as set forth.

MICHAEL C. HARNEY.
